[57] CLAIM

The ornamental design for a apparatus for honing piezo-electric crystals, as shown and described.

DESCRIPTION

FIG. 1 is a view in front elevation of my new apparatus for honing piezo-electric crystals, showing my new design;

FIG. 2 is a view of one side thereof;

FIG. 3 is a top plan view thereof;

FIG. 4 is a rear view thereof;

FIG. 5 is a view of the other side thereof; and

FIG. 6 is a bottom plan view thereof.

FIG. 3

FIG. 1

FIG. 2

FIG. 4

FIG. 5

FIG. 6
